(57) **CLAIM**

The ornamental design for a product holder, as shown and described.

DESCRIPTION

FIG. 1 is a perspective view of a product holder showing my new design.

FIG. 2 is a front elevational view thereof;

FIG. 3 is a rear elevational view thereof.

FIG. 4 is a left side elevational view thereof;

FIG. 5 is a right side elevational view thereof.

FIG. 6 is a top elevational view thereof; and,

FIG. 7 is a bottom elevational view thereof.

In the drawings, the broken lines depict portions of the article that form no part of the claimed design.
